CLAIM

The ornamental design for a wireless charging pad, as shown and described.

DESCRIPTION

FIG. 1 is a top view of a wireless charging pad, in accordance with our new design.

FIG. 2 is a left end view of the wireless charging pad, in accordance with our new design.

FIG. 3 is a right end view of the wireless charging pad, in accordance with our new design.

FIG. 4 is a front view of the wireless charging pad, in accordance with our new design.

FIG. 5 is a back view of the wireless charging pad, in accordance with our new design.

FIG. 6 is a top perspective view of the wireless charging pad, in accordance with our new design; and,

FIG. 7 is a top perspective view of the wireless charging pad installed in the ground when in use for charging a vehicle, in accordance with our new design.

In the drawings, the broken lines on the wireless charging pad depict unclaimed portions of the wireless charging pad and form no part of the claimed design. The broken lines shown in FIG. 7 depict environmental subject matter and form no part of the claimed design.

1 Claim, 7 Drawing Sheets
